JOHAN HUGO WALLIN AND KNUT GRANQVIST, OF KÖPMANHOLMEN, SWEDEN; SAID
GRANQVIST ASSIGNOR TO SAID WALLIN.

METHOD USED IN THE MANUFACTURE OF PAPER AND SUCH LIKE BY MACHINERY
TOGETHER WITH AN APPARATUS FOR THE PURPOSE.

1,186,629.

Specification of Letters Patent. Patented June 13, 1916.

Application filed November 14, 1913. Serial No. 800,998.

To all whom it may concern:

Be it known that we, JOHAN HUGO WALLIN and KNUT GRANQVIST, subjects of the King of Sweden, residing at Köpmannholmen, Sweden, have invented new and useful Improvements in Methods Used in the Manufacture of Paper and Such like by Machinery Together with an Apparatus for the Purpose, of which the following is a specification.

The present invention refers to a method used in the manufacture of paper and the like by machinery, consisting in causing the water running from, or pressed out of, some part of the wet-portion of the machine to act upon a registering device for indicating the thickness of the pulp in the machine, or a regulating device for controlling the supply of pulp to the machine, or both.

The invention relates also to an apparatus for carrying out this method, and this apparatus is more closely described hereafter with reference to the accompanying drawing. The apparatus shown on the latter is, however, only by way of example and diagram and may undergo many modifications, as will be seen from the following description.

From a certain part of the wet-portion of a drying and paper making machine, or similar contrivance which wet-portion substantially consists in the dandy-roller, couch-roller, and first or second pressure-roller, etc., cut preferably from the first felt-press, the water is run through a flexible tube 1 to a vessel 2 which is provided with an exhaust or outlet 3, preferably regulable. This latter should preferably be located near the bottom of the vessel. By making use of various sized nozzles the regulation of the outlet 3 is accomplished. The size of the outlet is determined according to the normal amount of water, that is to discharge a volume of water equal to the normal volume discharged into the vessel 2 from the wet portion of the machine when the pulp web is of proper thickness and in such a manner that when the volume of water running into the vessel is greater than the volume discharged therefrom, the water is made to run more slowly from the vessel than into the same, by which means the vessel is made to contain an amount of water varying according to the thickness

of the pulp in the machine, and by means of these variations the beforementioned registering and regulating devices are operated. However, when the pulp web is too thin, a smaller volume of water than normal will run into the vessel 2, but when the pulp web is too thick a larger volume of water than normal will run into the vessel 2, but the time interval between which the flow is not normal is so slight by reason of being corrected in a manner hereinafter explained, that said vessel will never overflow or become empty during the ordinary operation of the machine. According to the drawing this is done by means of a float 4 fitted in the vessel 2. Instead of making use of a float, the vessel 2 may also be attached to a pair of scales or similar device, or the said vessel may be developed into such, when the vessel itself or the scales will operate the said registering and regulating devices. The float 4 is, as shown in the drawings, connected through the medium of a chain or rod 5 with an indicator 6 which follows the movements of the float and moves along a scale 7 upon which the thickness of the pulp in the machine may be indicated directly or indirectly. In the modification just mentioned, when no float is used, the vessel or scales are connected with the indicator 6 instead.

The vessel 2 is shown divided by means of a wall 8 into two communicating compartments, the said wall not reaching the bottom of the vessel. The influx of the water takes place in one of the compartments, and the float 4 is fitted in the other, the quiet compartment, so as not to be affected by the surge or splash of the water caused through the influx of the water. According to the indicator 6 the influx of the pulp upon the wire-cloth is controlled by hand. The regulation just mentioned may, however, be effected automatically by means of any suitable device performing the finer regulation. The coarser regulation on starting, etc., is done by hand. A suitable automatic regulating device consists of an electric contact, such as the indicator 6 movable over and between electric contacts 20 and 21 which latter may be either fixed or movable, and this the first mentioned contact is actuated by the variations in the amount of water running off from, or pressed out of,

some part of the wet portion of the machine, or through the action of the aforesaid float, vessel, scales, etc., as the case may be. The indicator 6 controls the current in one or 5 more electric circuits operating suitable means, such as a motor, for operating the device for letting the pulp into the machine. According to the form of construction shown, 9 is a reciprocating rail running in 10 suitable guides, which rail may also be replaced by some other reciprocating member. This rail 9 has two oppositely operating latches 10, 11, which coöperate each with its electro-magnet 12 and 13 respectively and 15 with a common cog-wheel 14 for operating the devices for letting the pulp into the machine, which electro-magnets 12, 13 are excited by closing their circuits by means of the previously mentioned, movable, electric 20 contact member 6, so that first one and then the other latch is attracted by its electro-magnet and thus comes into such a position that during the movement of the reciprocating member, or the rail 9, it turns 25 the cog-wheel 14 in the direction determined for the respective latch. In the form of construction shown, the rail or bar 9 is made to slowly reciprocate through an adjoining axle by means of a belt 15, pulley 30 16, screw 17, worm-gear 18 and crank 19. The stroke may for example be 25 mm., dependent upon the spacing of the teeth in the cog-wheel 14. The movable contact or indicator 6 oscillates between the two contacts 20, 21, which may be fixed or adjustable by hand or automatically. A circuit is formed by the wire 22 with the battery 23, the support 24, the indicator 6, the contact 20, the wire 25 and the electro-magnet 40 12. If the pulp in the machine is getting thinner, less water runs from or is pressed out of the wet portion such as the pulp web, and consequently less water gets into the vessel 2, the level of the liquid in the latter sinks and thus also the float, which 45 results in the indicator 6 coming into contact with the contact 20 and closing the said circuit. The electro-magnet 12 then attracts its armature, which is the latch 10, which then occupies such a position that, when the rail 9 moves to the right, it engages the cog-wheel 14 and revolves the latter in the determined direction for turning 50 on more pulp, but on the rail moving 55 to the left merely glides over the teeth without revolving the cog-wheel. This goes on until the requisite thickness of the pulp has been reached, when the indicator 6 leaves the contact 20. Another circuit is 60 formed by the wire 22 with the battery 23, the support 24, the indicator 6, the contact 21, the wire 26 and the electro-magnet 13. When the pulp is getting too thick, a greater 65 volume of water runs from or is pressed out of the wet portion or pulp web at the wet

press, and consequently a greater volume of water runs into the vessel 2 to cause the water to rise therein and also the float so as to shift the movable contact produced by the indicator 6 to engage the contact 21 whereby the last-named circuit is closed in the same way and the latch 11 revolves the cog-wheel 14 in the opposite direction to the latch 10, until the thickness of the pulp has again become normal. When no current is passing through the electro-magnets 12, 13 the latches 10, 11 occupy the position shown in the drawing, so that the rail 9 may reciprocate without acting upon the cog-wheel 14.

The separate parts of the invention here referred to may vary as regards, material, shape, size, number and combination and may be transposed, provided the characteristics of the invention be retained.

We claim,—

1. In the manufacture of paper, or like material by machinery, a method for regulating the feed of pulp to the machine and indicating the thickness of pulp therein, by storing part of the fluid running from the pulp in the machine and then allowing the variations in the level of said stored fluid to indicate the thickness of the pulp in the machine and to control the supply of pulp to the machine.

2. In the manufacture of paper, or like material by machinery, a method of regulating the feed of pulp to the machine and indicating the thickness of pulp in the machine, by storing a quantity of the liquid running from the pulp in the machine, and then allowing the varying quantities of stored fluid to indicate the thickness of pulp in the machine and to control a supply of pulp to the machine.

3. In the manufacture of paper, or like material, by machinery, a method of regulating the feed of pulp to the machine and indicating the thickness of pulp in the machine, by partially storing fluid being pressed out of the pulp and flowing from the machine; then permitting the variations in quantity of the stored fluid, produced by the varying thicknesses of the pulp in the machine, to operate a registering device for indicating the thickness of pulp in the machine, and a regulating device for controlling the supply of pulp to the machine.

4. An apparatus of the character described, and adapted for use with a paper machine, comprising a vessel to receive liquid pressed from the material in said machine and adapted to discharge a volume of liquid equal to the normal volume received from said material when the same is of proper thickness, a float disposed in said vessel and adapted to rise and fall according to the variations of level of said fluid in the vessel, produced by the varying thicknesses of the material in the machine, and

indicating means connected with said float for indicating the thickness of the material in said machine.

actuated by the varying quantities of liquid in the vessel, produced by the varying thickness of material in the machine, and means controlled by said indicating means whereby 65 the feed of material to the machine is controlled according to the variation in thickness of the material in the machine.

5. An apparatus of the character described, a paper making machine, comprising a vessel to receive liquid pressed from the material in said machine and adapted to discharge a volume of liquid equal to the normal volume received from 10 said material when the same is of proper thickness, a float disposed in said vessel and adapted to rise and fall according to the variations of level of said fluid in the vessel, produced by the varying thicknesses of the 15 material in the machine, and means controlled by said float whereby the feed of the material to the machine is controlled according to the variations in thickness of the material in the machine. 9

6. An indicating and controlling apparatus for use in a paper making machine, comprising a vessel to receive liquid pressed from the material in said machine and adapted to discharge a volume of liquid 20 equal to the normal volume received from said material when the same is of proper thickness, a float disposed in said vessel and adapted to rise and fall according to the variations of level of said fluid in the vessel, produced by the varying thicknesses of the 25 material in the machine, and indicating means connected with said float for indicating the thickness of the material in said machine, and means controlled by said indicating means whereby the feed of material to the machine is controlled according to the variation in thickness of the material in the machine. 30

7. An indicating and controlling apparatus for use in connection with a paper machine, comprising a vessel to receive liquid pressed from the material in said machine and adapted to discharge a volume of liquid equal to the normal volume received 35 from said material when the same is of proper thickness, means associated with the vessel and actuated by the varying quantities of liquid in the vessel, produced by the varying thickness of material in the machine, indicating means connected with said first mentioned means for indicating the thickness of the material in the machine. 40

10. An indicating and controlling apparatus adapted to cooperate with the press of a paper making machine, comprising a measuring device for indicating the amount of material in said machine, electric circuits 45 connected with the said measuring device, a source of electrical energy for said circuits, a reciprocating member, spaced and oppositely disposed pawls carried by said member, a toothed wheel controlling the feed of 50 material and adapted to be engaged by said pawls and to receive motion therefrom, an electro-magnet for each of said pawls and disposed in said electric circuits, said magnets being adapted to be energized and to 55 operate said pawls alternately according to the operation of said measuring device, whereby the operation of said toothed wheel is controlled. 60

In testimony whereof we have signed our 115 names to this specification in the presence of two subscribing witnesses.

8. An indicating and controlling apparatus of the character described, for use with the wet portion of a machine, comprising a vessel to receive liquid pressed from the material in said machine and adapted to discharge a volume of liquid equal to the normal volume of liquid received from said 65 material when the same is of proper thickness, means associated with the vessel and
